CLAIM

The ornamental design for a gaming machine, as shown and described.

DESCRIPTION

FIG. 1 is a front perspective view of a gaming machine showing our new design;

FIG. 2 is a front view of the gaming machine design shown in FIG. 1;

FIG. 3 is a back view of the gaming machine design shown in FIG. 1;

FIG. 4 is a right view of the gaming machine design shown in FIG. 1;

FIG. 5 is a left view of the gaming machine design shown in FIG. 1;

FIG. 6 is a top view of the gaming machine design shown in FIG. 1; and,

FIG. 7 is a bottom view of the gaming machine design shown in FIG. 1.

Broken lines illustrate unclaimed environmental features and form no part of the claimed design.
